CLAIM

The design of an injector device, as shown and described.

DESCRIPTION

FIG. 1 is a top, front, right perspective view of an injector device showing our new design;

FIG. 2 is a front elevation view thereof;

FIG. 3 is a rear plan elevation view thereof;

FIG. 4 is a top plan view thereof;

FIG. 5 is a bottom plan view thereof;

FIG. 6 is a left side elevation view thereof; and,

FIG. 7 is a right side elevation view thereof.

In a preferred embodiment, the nature of the design is an injector device for delivering pharmaceutical agents.

The dashed line portion of the drawings is included to show unclaimed subject matter only for the purpose of illustrating environment and forms no part of the claimed design. The dash-dot line portions in the drawings define a boundary of the claimed design and form no part thereof.
